SEALED BEAM LAMP

Elam Pitkjaan, Cedar Grove, N.J., assignor to Westinghouse Electric Corporation, a corporation of Pennsylvania

Filed Dec. 19, 1966, Ser. No. 5,112

Term of patent 14 years

(Cl. D48—32)

FIG. 2.

FIG. 1.

FIG. 3.

FIG. 5.

FIG. 4.

FIG. 6.

FIGURE 1 is a front elevational view of a sealed beam lamp embodying my new design;

FIG. 2 is a top plan view of the lamp shown in FIG. 1;

FIG. 3 is a side elevational view of the lamp shown in FIG. 1; and

FIGS. 4, 5 and 6 are views corresponding to FIGS. 1 to 3, respectively, of another embodiment of my new design.

The side views of the lamps not shown in the drawings are identical to those which are shown.

The broken line showing of the lens flutes in FIGS. 1 and 4, respectively, are merely representative of a conventional lens pattern.

The dominant features of my new design are shown in full lines.

I claim:

The ornamental design for a sealed beam lamp, substantially as shown and described.
